PAPER MAKING MACHINERY

Joseph E. Bond, Middletown, Ohio

Application November 9, 1933, Serial No. 697,314

6 Claims. (Cl. 92—20)

This invention relates to the art of making paper and the like and more particularly to pulping and refining apparatus for disintegrating and refining paper pulp.

5 One of the principal objects of the invention is the provision of an efficient and effective method and means of pulping in which a refining action is carried out at a consistency as high as 10% or more.

10 Another object of the invention is the provision of a method of refining pulp at very high consistency in which some of the pulp or stock is supplied from a circulating system to a confined refining action.

15 Other objects and advantages of the invention will be apparent from the following description, the appended claims and the accompanying drawings, in which

20 Fig. 1 is a plan view of an apparatus embodying and for practicing the present invention;

Fig. 2 is a side elevation of the apparatus;

Fig. 3 is a vertical section of the apparatus taken on the line 3—3 of Fig. 1; and

25 Fig. 4 is a vertical section taken on the line 4—4 of Fig. 4.

In accordance with the present invention paper pulp and the like is broken up or defibered by the utilization of apparatus which effectively circulates the stock within and through the part 30 of movement of mechanisms for causing disintegration or defibering of the fibrous material, bundles, laps, etc. Such action is desirably accomplished and obtained by means of rotatable blades which revolve at high speed while acting 35 on very high consistency stock and which are so constructed that in operation they hold back a lap or bundle of stock while playing upon it and shredding, whirling and breaking up the pulp into smaller pieces, which are then forced along 40 so that some of the pulp pieces of large size are returned to the main supply of pulp or stock in the circulating vat or tank, while the more completed defibered stock is supplied under pressure to the inlet of, and is fed into, a refiner. The 45 stock pieces and fibers taken into the refiner are as high as 10% or more in consistency, the thick stock being brushed, rolled, and straightened in the refiner by the action of relatively rotatable oppositely spiralled blades in the casing and plug 50 of the refiner.

Referring more particularly to the drawing by reference numerals, 10 designates generally a vat or tank having a midfeather 11 suitably arranged to provide for substantially unobstructed circulation of the stock around the midfeather and

along the sides of the tank. The bottom of the tank is sloped so that the stock tends to flow by gravity from the floor portion 12 along to the portion 13 in a continuous and unobstructed manner.

Extending between the midfeather 11 and the outer wall of the vat is a partition or wall 15, and at one side of the partition the vat has a large opening 16, preferably rectangular in shape, into which the pulp or stock passes after completing 10 a circuit of the vat. After passing through the opening 16 which is preferably large enough to accommodate an entire pulp lap or sheet, the stock, as herein shown, flows through a rectangular casing portion or pipe 17 which may extend 15 from the tank or vat, and passes to the stock breaking apparatus including a suitable pump. The pump is effective to force the stock along suitably, at a consistency of 10% and even up to 14%. The pump forces some of the stock along 20 through a pipe 19 and into the space 25 above the wall 15, the stock circulating continuously 25 around the midfeather and back to the suction opening 16.

The breaking means as more fully set forth in 30 my copending application, Serial No. 697,311, filed November 9, 1933 may comprise a plurality of breakers designated by the numerals 28 and 33, constructed to hold back bundles of stock drawn forward by the pumping action while playing 35 upon them in the space 27. These blades are preferably all secured on the shaft 29 which is connected to a reversible electric motor 30 adapted to rotate the blades at high speed. The faces of the blades 28 and 33 are suitably inclined to 40 the plane of rotation for propelling effect, and the end blades 28 are inclined axially in a rearward direction so as to prevent the pulp pieces from clogging or piling up adjacent the end of the shaft. The peripheral speed of blades 28 of 45 a diameter of about 19 inches and using stuff of 12% consistency, may be of the order of a mile per minute. The bundles of stock which are supplied to the tank and which flow into the inlet or suction opening 16 are held back by the blades 45 which at the same time play upon the bundle and break up the pulp by whirling and whipping it until it is so shredded and torn apart as to be in condition to go to the circulating impact type impeller blades 35 provided within the smaller end of the passage 32. The breaker blades are 50 effective in tearing and breaking the pulp as its high consistency causes a high resistance to be set up. The impeller blades 35 draw the pulp or stock along and force some of it up through the 55

pipe 19 so that it is returned to the vat to be circulated therein.

While reference is made herein to bundles of stock or pulp, other forms of fibrous material such as for example printed papers, broke, etc., are to be included in the terms used.

The stock that is returned to the tank through the pipe 19 and which passes through the space 25 above the partition 15 circulates around the midfeather and returns again to the inlet or suction opening 16. Some of the stock returned to the space 25, however, flows through openings 36 in the partition 15 instead of circulating around the midfeather, and passes downwardly so as to flow on to the pulp in the vat which is passing or ready to pass in the suction opening 16. The advancing bundles or overlapping pulp sheets are thus effectively submerged or turned down at their advancing ends so as to more readily enter the suction opening.

Only a part of the pulp or stock passing the breaking blades 28 and 33 is returned directly to the tank, however, the remainder being supplied under the pressure obtaining at the outlet side of the impeller blades 35 to the inlet side of the tapered casing of a refiner. This refiner, designated generally by the reference numeral 45, see Figs. 1 and 4, comprises the tapered casing 46, the inlet side of which is of smaller diameter and opens into the passage 19 so as to be supplied with stock that has been passed by the breaking blades 28 and 33. The casing 46 contains a series of spaced bars which are preferably of spiral or volute shape. The distance between adjacent bars, which may be about forty in number, may be made about the same as bar width. Rotatably fitting within the case is the tapered plug 47 carried by the shaft 29, the plug also carrying spiral or volute shape bars suitably spaced apart, the bars of the plug curving oppositely than the bars in the casing. The space between the bars of the plug and casing may be adjusted by longitudinal adjustment of the bearing housing 49 by means of an adjustable threaded stop member 50. A hydraulic control comprising the piston 51 contained in the cylinder 52 and connected to the bearing housing 49 is preferably supplied to govern the position of the plug shaft of the refiner and to hold the plug towards the smaller end of the casing against the adjustable stop member during operation. The oppositely spiraling character of the blades on the plug and casing of the refiner is such as to cause an efficient brushing and rolling or straightening action and also an effective pumping action so that the stock may be supplied to the discharge pipe 53 from which it may either be sent back to the tank 10 or may be supplied to a desired point of use.

The refiner 45 is supplied with pulp or stock of as high as 10% and up to 14% consistency, and produces an effective defibering, rolling, straightening and brushing action on the stock, refining it so that it is in condition to pass to a point of use, or if the breaking up or pulping action is not fully completed, for return to the tank 10. Before the stock bundles in the tank are thoroughly broken up and shredded the clearance between the bars of the plug and casing may be quite substantial thus straightening out the stock pieces and treating them with a gentle breaking up action, but when the system has been operating a suitable time and the defibering action is nearly or fully completed the clearance may be reduced to produce a more effective brushing and refining action. As will be apparent from Fig. 4

the entrance of small pulp or stock pieces into the refiner is assisted by propelling blades 55 provided on shaft 29 at the inlet end of the refiner at a suitable inclination of blade face for effective propelling effect. The stock is received by these blades 55 under a considerable head or pressure, since the inlet of the refiner is close to the pressure side of impact blades 35. A baffle plate or disk 56 is preferably arranged on the shaft 29 a short distance from the blades 55 and between them and the impact blades 35 so that large pieces of pulp will tend to travel up the passage 19 rather than going into the refiner. The smaller pieces of pulp and the defibered stock, however, can flow freely under pressure and be drawn under the suction effect of the blades 55 into the refiner so as to be more effectively refined before being supplied to a point of use. Inasmuch as the discharge end of the refiner is at a substantial pressure head the action of the refiner is quite thorough, and very effective and a continuous flow through the refiner is assured since the flow to the refiner is under considerable pressure and also by reason of the pumping action of the refiner itself.

The refiner is effective in forcing a flow of the high consistency stock while acting upon the stock to produce a more thorough refining action than that obtained by the blades 28 and 33, and the combination of the rapidly whirling blades 28 and 33 and the action obtained in the refiner 46 is such as to produce a stronger sheet of paper with a marked saving in power. The capacity of the system is greater and the power requirements less for the high consistency stock since the amount of material present is less than would be the case if stock of the ordinary consistencies were treated.

While the method herein described, and the form of apparatus for carrying this method into effect, constitute preferred embodiments of the invention, it is to be understood that the invention is not limited to this precise method and form of apparatus, and that changes may be made in either without departing from the scope of the invention which is defined in the appended claims.

What is claimed is:

1. Apparatus for the treatment of paper pulp at high consistency comprising a tank for receiving paper pulp, a passage extending from said tank and returning back to the tank, rotary high speed beater blades in said passage for whirling and pulping the stock, a flow controlling partition in said tank between the inlet and outlet sides of said passage, a tapered casing having an inlet opening in communication with the outlet side of said blades and ahead of the point of return to the tank, and a tapered plug rotatably fitting within said casing, said plug and casing having cooperating blades for refining the stock.

2. Apparatus for the treatment of paper pulp at high consistency comprising a tank for receiving paper pulp, a passage extending from said tank and returning back to the tank, rotary high speed beater blades in said passage for whirling and pulping the stock, a flow controlling partition in said tank between the inlet and outlet sides of said passage, a tapered casing having an inlet opening in communication with the outlet side of said blades and ahead of the point of return to the tank, propelling blades at the inlet opening of said casing for forcing material into said casing, and a tapered plug rotatably fitting within said casing, said plug and casing having cooperating blades for refining the stock.

3. Apparatus of the character described for pulping at high consistency comprising a pulp passage, high speed rotary blades in said passage but spaced radially from the walls of said passage and adapted to shred, whirl and pump the pulp while holding back a bundle of pulp, a return passage for circulating said pulp back to said blades, a tapered casing having its inlet end in communication with the discharge side of said blades, propelling means at the inlet end of said casing, a baffle member between said blades and propelling means, and a tapered plug rotatably fitting within said casing and cooperating therewith to refine the pulp entering the casing.
- 5 4. Pulping apparatus of the character described for pulping at high consistency comprising a tank for receiving pulp, a passage extending from the tank and returning to a higher point in the tank, said tank being adapted for the 10 circulation of the pulp in an unobstructed manner from the outlet of said passage to the inlet thereof, a high speed rotary beating blade in said passage for whirling and breaking the stock while the stock is substantially unconfined, a tapered casing having its smaller end in communication with said passage between said blade and the point of return to the tank, and a tapered 15 plug rotatably fitting within said casing, said casing and plug having oppositely spiralled bars for refining the pulp entering said casing.
- 5 5. Breaking apparatus of the character described for pulping at a consistency of 10% or more comprising high speed rotary blades for whirling and breaking the pulp and forcing it along, a tapered casing having its smaller end at the discharge side of said blades, and a tapered 10 plug rotatably fitting within said casing, said casing and plug having oppositely spiralled bars for refining the pulp entering said casing.
6. Apparatus for the treatment of paper pulp comprising a circulating tank adapted for unrestrained circulation of paper pulp, high speed 15 rotary blades for whirling, beating and breaking up the stock while the stock is substantially unconfined, a casing having an inlet opening adapted to receive stock that has been whirled and broken up by said blades, stationary casing blades 20 for said casing, and a rotatable plug in said casing having blades cooperating with the casing blades for refining and rolling the stock, said casing having a discharge passage for returning the stock to the tank for circulation to said high 25 speed rotary blades.
